US0D1040819S

(12) **United States Design Patent** (10) Patent No.: **US D1,040,819 S**
(45) Date of Patent: ** Sep. 3, 2024

(54) **DISPLAY SCREEN OR PORTION THEREOF WITH A GRAPHICAL USER INTERFACE**

(71) Applicant: **Beijing Bytedance Network Technology Co., Ltd.**, Beijing (CN)

(72) Inventors: **Zhiwei Li**, Beijing (CN); **Renbo Zhu**, Beijing (CN)

(73) Assignee: **BEIJING BYTEDANCE NETWORK TECHNOLOGY CO., LTD.**, Beijing (CN)

(**) Term: **15 Years**

(21) Appl. No.: **29/814,540**

(22) Filed: **Nov. 5, 2021**

(30) **Foreign Application Priority Data**

May 7, 2021 (CN) 202130270544.0

(57) **CLAIM**

We claim the ornamental design for a display screen or portion thereof with a graphical user interface, as shown and described.

DESCRIPTION

FIG. 1 is a front view of a first embodiment of a display screen or portion thereof with a graphical user interface showing our new design; and,

FIG. 2 is a front view of a second embodiment thereof. The outermost broken line rectangle illustrates a display screen or portion thereof and forms no part of the claimed design. The remaining broken lines illustrate portions of the graphical user interface that form no part of the claimed design.

1 Claim, 1 Drawing Sheet
